UNITED STATES PATENT OFFICE.

TONJES AUGUST CARL BOTH, OF MALDEN, MASSACHUSETTS, ASSIGNOR TO THE ZEE SOCKET AND MFG. CO., OF BOSTON, MASSACHUSETTS, A CORPORATION OF MASSACHUSETTS.

SOCKET-SHELL.

1,108,547.

Specification of Letters Patent. Patented Aug. 25, 1914.

Application filed August 7, 1912. Serial No. 713,770.

To all whom it may concern:

Be it known that I, TONJES AUGUST CARL BOTH, a citizen of the United States, and a resident of Malden, in the county of Middlesex and State of Massachusetts, have invented a certain new and useful Improvement in Socket-Shells, of which the following is a specification, taken in connection with the accompanying drawings, which form a part of the same.

My invention relates to casings for electrical apparatus.

More particularly it relates to socket shells and to removable insulating linings for the caps of such socket shells which are located within the caps without bending or otherwise marring any portion of the insulating linings and there secured by any suitable means mounted on the exterior of the caps.

I have shown by way of example four forms of my invention, but it is, of course, to be distinctly understood that these are mere examples, and that various modifications may be employed, all coming within the terms of my claims.

In the accompanying drawings, showing illustrative embodiments of my invention and in which the same reference numerals refer to similar parts in the several figures—Figure 1 is a side elevation of my invention applied to an electric light socket shell; Fig. 2 is a central vertical section through the cap showing the preferred form of my invention; Fig. 3 is a detail perspective view of the insulating lining for the cap; Fig. 4 is a longitudinal vertical section through the cap showing a modified form; and Fig. 5 is a side elevation of the cap illustrating a different exterior locking means for securing the insulating lining within the cap. Fig. 6 is a side elevation of a modification; Fig. 7 is a fragmentary horizontal section substantially on line 7—7 of Fig. 6, and on a smaller scale than said Fig. 6.

It has been old prior to my invention to use a removable insulating lining for the cap of socket shells which was held within the cap by some locking or fastening mechanism on the interior of the cap, the insulating member, or some portion of it, being sprung or bent to pass over some obstruction or projection, reliance being placed upon the insulating member again springing out into its original condition to coöperate with the

interior projections so as to prevent the insulating lining from falling out of the cap. These insulating linings are usually made of fiber, as is well known in the art, and are usually cut away to form notches or other surfaces to coöperate with shoulders or surfaces within the cap.

In practice immense numbers of electric light sockets and their casings are sold to manufacturers of electric fixtures to be assembled with the other portions of the fixtures made, or assembled, by such manufacturers. It is frequently necessary for such manufacturers to refinish or replate the socket casing, including the cap, to match or harmonize with the particular electric fixture of which it is to be a part. Before such replating or refinishing, however, it is necessary to remove the insulating lining from the socket shell. The lower fiber lining or insulating lining, which insulates the shell portion of the socket, readily slips out of the shell so that its removal does not mar it or require any particular care. The removal of the lining from the cap, however, is quite a delicate operation for the lining has to be pried off or otherwise removed from the interior locking mechanism, mounted on the interior of the cap, and which coöperates with the notches, fingers, or other portions of the insulating lining, to hold it in its position within the cap. This frequently mars the insulating lining. The frequency and extent of the damage to the lining would depend upon the labor employed for this purpose. Usually unskilled labor is employed with the result that large numbers of the insulating linings have been either ruined by being removed from the interior locking surfaces in the cap, or have been so torn or marred that when they were again placed in the cap, after it has been replated or refinished, it was liable not to retain its position and the tears or cracks in the lining caused by its removal and repositioning would often defeat the very purpose of providing the cap with an insulation to prevent it from becoming electrified with possible damage to the fixture or shock to the person who may be handling it after the fixture has been installed. Often the interior insulating lining was so torn or marred that it could not be placed back in the cap and consequently either a new lining had to be substituted or, if one was not at hand, the manufacture of

the entire electric light socket, or the entire fixture of which it was to form a part, would have to be delayed until a new lining could be obtained. In some cases where unskilled labor was employed and speed in reassembling the sockets after replating was demanded by the employer no lining would be placed in some of the sockets. There was no means of detecting this oversight or carelessness without disassembling each one of the sockets which was laborious and would require considerable time of the operator. By my invention I avoid bending or otherwise marring the insulating lining and use an exterior locking means of any construction mounted on the exterior of the cap to secure the lining within the cap. By my invention also a small finger of the lining is visible from the exterior of the socket casting so that the merest glance at the assembled shell will determine whether or not a lining has been placed within the cap. The removal of the lining is expedited, its life is greatly increased, and the inspection of the complete sockets to determine whether or not a lining has been placed in the cap, is greatly facilitated.

In the illustrative embodiments of my invention shown in the drawing, 1 is a socket cap provided with the removable insulating lining 2. This insulating lining while usually of fiber may be made of porcelain or any suitable insulating material. If of fiber it can be made much thicker and stronger than 35 it could be if it coöperated with interior locking shoulders or surfaces mounted within the cap and over which it had to be bent or sprung. I have shown by way of example my insulating lining 2 provided with suitable fingers 3, 3 which coöperate with the slots 4, 4 within the cap 1. These slots 4, 4 are simply stamped or cut out of the cap and are formed large enough to readily receive the fingers 3, 3. For purposes of illustration I have shown the slots 4, 4 somewhat exaggerated. The preferred form of assembling the cap and insulating lining is simply to invert the cap 1, from the position shown in Fig. 2, and drop the lining 2 within the cap, the fingers 3, 3 dropping until their further downward movement is stopped by the edges 5, 5 of the slots 4, 4. This operation is accomplished without flexing, bending or otherwise distorting the fingers 3, 3 or any portion of the insulating lining 2.

After the insulating lining has been dropped into the cap 1, as previously described, it may be held in that position by any exterior locking means. I have shown 60 by way of example a resilient split wire ring 6 of any suitable material which may be removably sprung around the exterior of the cap 1 and beneath the fingers 3, 3. Preferably the cap is provided with a circumferential groove 7, for the reception of the re-

silient ring 6, though this is not essential as I will hereinafter describe the structure shown in Fig. 4 in which no circumferential groove is employed.

It is obvious that after the insulating lining is mounted in the cap it cannot be removed until the wire or similar member 6 is removed from engagement with the fingers 3, 3. In replating or refinishing the electric light socket, which is formed of the cap 1 and the shell 8, Fig. 1, it is merely necessary to pry off the resilient ring 6 which will permit the insulating lining 2 to drop out of the cap 1 without the necessity of bending or flexing any portion of it with the consequent damage to the insulating lining. After the cap 1 has been replated or refinished in any suitable manner, the insulating lining 2 can be again dropped into the cap, as previously described, for the original assembling of the parts.

As the fingers 3, 3 which are purposely shown exaggerated in the figures of the drawing, will show from the exterior of the reassembled socket, Fig. 1, it is possible to inspect the complete socket after it is assembled, or reassembled, to determine whether or not they have been equipped with the insulating lining for the cap. It is of course understood that the shell 8 is provided with the usual form of cylindrical insulation which can be easily slipped out of the shell, but as this forms no part of my invention I have not shown it. Frequently the socket shells are equipped with a key 9 to operate a switch mechanism if one is employed. This, however, is no part of my present invention.

In some cases, I may employ a cap 10 having the usual offset 11 and in the cap form 105 one or more slots 12, by stamping or otherwise, to receive the fingers 3, 3 of the insulating lining 2. The insulating lining in this form is assembled by dropping it into the cap 10, after reversing the cap from the position shown in Fig. 4 which will bring the fingers 3, 3 into engagement with the stops 13, 13 of the cap. I also use in this form of my invention a similar exterior locking means which is preferably though not necessarily a resilient split ring 6.

Instead of using a removable exterior locking means to coöperate with the fingers, or other parts carried by the insulating lining 2, I may form a cap 14 having the usual offset 15 and provide it with suitable slots 16 for the reception of the fingers 3, 3 which are dropped into the cap 14 in the manner previously described at length for the other forms. In this form, however, instead of using a removable locking means I employ permanent locking means as for example the spring arms 17, 17 pivoted on the pins 18, 18. In practice the insulating lining is dropped into the cap 14 in the manner previously de- 125

scribed, the pivoted arms 17, 17 having been first moved on their pivots so as to permit the free entry of the fingers 3, 3. Then by swinging the arms upon their pivots, and if necessary springing them out, they preferably being formed of spring material, they will become seated beneath the fingers 3 and will hold the insulating lining within the cap. The friction and resiliency of the 10 spring arms is usually sufficient to prevent any movement of the insulating lining with relation to the cap. In some cases I may use one or more resilient members secured at both their ends by a sliding connection with 15 the cap, the resilient members being pried out to permit the withdrawal of the lining. In Fig. 6 I have shown such a construction in which the cap 20 is provided with one or more, preferably two, pieces of wire or similar material 21, the ends of which have a sliding connection with the punched up ridges 22, 22. In assembling the insulating lining 2 in this form of my invention, the lining is dropped into the cap 20, the same 20 as in the other forms, the fingers 3, 3 being received in the slots 23. The ends of the short pieces of wire 21 may then be threaded into the different ridges 22, 22. If the wire or other resilient member 21 was first mounted 25 on the exterior of the cap, before the insertion of the insulating lining 2, it can be pried out slightly to permit the passage of the finger 3 after which it will spring back into position beneath the finger and prevent 30 the removal of the insulating lining until the wire or wires 21, 21 are again sprung out to permit the withdrawal of the lining 2 for replating or refinishing of the socket casing, as previously described. After such replating 35 the cap and interior lining will be reassembled as described.

Having thus described this invention in connection with several illustrative embodiments thereof to the details of which I do not desire to be limited, what is claimed as new and what it is desired to secure by Letters Patent is set forth in the appended claims.

1. In an electrical apparatus the combination of a casing provided with apertures, a removable insulating lining provided with fingers or projections to coöperate with the apertures and exterior means mounted on the outside of the casing and coöperating 55 with the insulating lining to hold it within the casing.

2. In an electrical apparatus the combination of a casing provided with apertures, a removable substantially rigid insulating lining provided with fingers or projections to coöperate with the apertures and exterior means mounted on the outside of the casing and coöperating with the substantially rigid insulating lining to hold it within the casing.

3. In electric light sockets, the combination of a cap having an offset portion and slots, an insulating lining mounted in the cap and provided with means to coöperate with the slots, and resilient means coöperating with the offset portion and the means carried by the insulating lining to secure the lining within the cap. 70

4. In electric light sockets, the combination of a cap having an offset portion and 75 slots, an insulating lining mounted in the cap and provided with means to coöperate with the slots, and a split ring to coöperate with the offset portion of the cap and with the means carried by the insulating lining to 80 secure the latter within the cap.

5. In an electrical apparatus, the combination of a casing, an insulating lining mounted wholly within the casing, and means separable from the casing and mounted on its exterior adapted to coöperate with the casing and the insulating lining to hold the latter within the casing. 85

6. In an electrical apparatus, the combination of a casing, an insulating lining 90 mounted wholly within the casing, and resilient means separable from the casing and mounted on its exterior adapted to coöperate with the casing and the insulating lining to hold the latter within the casing. 95

7. In an electrical apparatus, the combination of a casing provided with an exterior circumferential abutment, an insulating lining, and means separable from the casing and mounted on its exterior and coöoperating 100 with the exterior circumferential abutment and with the insulating lining to hold the latter within the casing.

8. In an electrical apparatus, the combination of a casing provided with an exterior circumferential groove, an insulating lining, and resilient means mounted in the exterior groove of the casing and coöperating with the insulating lining to hold the latter within the casing. 105

9. In an electrical apparatus, the combination of a cylindrical casing provided with circumferential openings, an insulating lining provided with means to coöperate with the circumferential openings, and means 115 separate from the casing mounted on the circumference of the casing and coöperating with it and the insulating lining to hold the latter within the casing.

10. In electric light sockets, the combination of a cap provided with a skirt and with openings in its side wall, a fiber lining provided with means to coöperate with the openings and means separate from the cap and mounted adjacent to the skirt and on the 120 exterior of the cap adapted to coöperate with the fiber lining to hold it within the cap. 125

11. In electric light sockets, the combination of a cap with circumferential openings, 130

and an insulating lining provided with means extending into the openings so that said means carried by the lining will be visible on the exterior of the cap to permit ready inspection of the sockets, and means coöoperating with said first means to hold the insulating lining in the cap.

12. In electric light sockets, the combination of a cap provided with circumferential

openings, and an insulating lining provided with members extending into the circumferential openings to permit ready inspection of the sockets, and means to hold the insulating lining in the cap.
